UNITED STATES PATENT OFFICE

WILFRED A. BEAUCHAMP, OF CHICAGO, ILLINOIS, ASSIGNOR TO CAMEL COMPANY, OF CHICAGO, ILLINOIS, A CORPORATION OF ILLINOIS

CAR CONSTRUCTION

Application filed February 5, 1930. Serial No. 425,962.

This invention relates to car construction and is directed primarily to the side sill structure of railway house cars.

An object of the invention resides in the novel arrangement of side sills, whereby said sills are adapted to serve as tracks for sliding doors.

A further object is the provision of side sills adapted to function as tracks for sliding doors and permitting, without modification, the use of the customary connections between said sills and connecting members.

An object, also, is the provision of side sills adapted for employment as tracks for sliding doors whereby the section modulus of said sills is increased.

An object, as well, is the provision of side sills which may be employed as tracks, thereby eliminating separate tracks and track brackets customarily employed.

An object, moreover, is the use of side sills serving as tracks for sliding doors and which permit the positioning of hangers for said doors closer to the car, whereby danger of injury to said hangers by side swiping is greatly minimized.

Other objects and advantages will become apparent from the description of the invention taken in connection with the drawings forming a part thereof in which:

Figure 1 is an elevation of a house car embodying the invention and having a pair of bottom supported doors mounted for sliding movement.

Figure 2 is a section taken on line 2—2 of Figure 1.

Figures 3 and 4 are similar sectional views, showing modified constructions embodying the invention.

Referring to the drawings, the numeral 10 designates a railway house car on which doors 11—11 are mounted for sliding movement. The doors as shown are provided with corrugated metal panels, although it is to be understood that any preferred type of door

construction may be employed. Bottom hangers 12—12 are used for mounting said doors. At the upper margins of the doors brackets 13—13 are employed, said brackets limiting inward movement of the doors, while outward movement is limited by the engagement of said margins with the lower flange of the side plate 14. A starting and closing mechanism is indicated in its entirety by the numeral 15. The numeral 16 designates as a whole a latching and sealing device for the doors. While a pair of doors is shown, it is to be understood that the invention is not limited thereto, but may be employed with a single door as well.

The side sill of the present invention is denoted by the numeral 17. This sill, as clearly shown in Figure 2 of the drawings, comprises a substantially vertical web 18, from the upper margin of which a substantially horizontal flange 19 projects. At the lower margin of said web there is provided oppositely extending flanges 20 and 21. Positioned between the web 18 and the metallic sheathing 23 of the car and secured thereto is a Z shaped member 22. It is obvious from the foregoing that the side sill thus presents an unobstructed web facing outwardly of the car and a channel construction facing inwardly thereof, permitting the usual and accepted attachments of car sheathing and car underframing respectively to said sill. The downwardly depending leg of the Z-bar 22, carried by the side sill, provides means which is engageable with upwardly extending flanges 24 on the hangers 12 to limit outward movement of the lower part of the door.

The flange 21 of the sill 17, as clearly shown in Figure 2 of the drawings, extends laterally beyond the car and is spaced a suitable distance below the floor 25. This flange 21, of the side sill construction by virtue of its position relative to the car is rendered capable of serving as a track for the doors 11—11. Moreover, said track flange, in view of its lat-

eral extension relative to the car, enables the door supporting hangers to be positioned in close proximity to said door and so avoid any substantial offset relationship between said door and the rolling means of the hangers. The foregoing is illustrated in Figure 2 of the drawings and also in Figures 3 and 4 of the drawings showing modifications of the invention, the relationship between the door and the rollers of the hangers being clearly apparent.

Figure 3 of the drawings illustrates a modification of the construction shown in Figures 1 and 2, in that a Z-bar side sill 26 is employed, rather than the side sill 17.

In Figure 4 of the drawings there is shown a modification illustrated as applied to a single sheathed car, although it is to be understood that the modification shown in this figure is not limited to such car construction. The side sill 27 shown in this figure takes the form of a substantially W shaped member having a laterally extending flange 28 which projects beyond the car and serves as track means adapted to support doors for sliding movement. The door is supported upon said flange by means of hangers 29, said hangers being provided with upwardly extending flanges 30 adapted to cooperate with the downwardly extending flange 31 of the sill in order to limit outward movement of the lower portion of the door. The flange 31 additionally serves to strengthen the flange 28, which latter flange may serve as a support for stationary posts or braces 32 secured to said flange and to the web of the side sill by means of gusset members 33. In another aspect of the embodiment of the invention shown in Figure 4 the side sill takes the form of a Z shaped member of which the flange 28 serves as a track. This flange is provided with the downwardly extending flange 31 adapted to function as hereinbefore set forth. It is to be understood that the track flanges of the constructions shown in Figures 2 and 3 of the drawings may embody a downwardly directed flange similar to the flange 31 shown in Figure 4 of the drawings. In this event the member 22 may be dispensed with and hangers similar to hangers 29 will be substituted for the hangers 12.

It is apparent that numerous modifications and changes may be made in the details of the embodiments set forth without departing from the spirit of the invention and all such modifications and changes are deemed to be included in said invention which is not to be limited except as indicated by the scope of the claims appended hereto.

60 I claim:

1. In combination, a car body, a side sill, a door opening in said car body, said sill being so constructed and arranged relative to said door opening as to constitute a track for a door provided on said car body and a flange

provided on said sill and forming guide means for said door.

2. A side sill for railway house cars comprising, a structural member embodying a substantially vertical web, a substantially horizontal flange at the upper margin of said web, and oppositely extending flanges at the lower margin thereof, said web having secured thereto a member presenting a downwardly extending flange.

3. The combination with the side posts and braces of a house car, of a side sill, said sill having a flange positioned below said posts and braces, gusset members rigidly connecting said flange and posts and braces, said flange extending laterally of said posts and braces and constituting a track for a door provided thereon.

4. A structural member adapted for use in side sill construction for railway house cars comprising, a substantially W shaped member, one of the flanges of said member being positioned substantially horizontal and another of the flanges of said member depending from said first mentioned flange and adapted to serve as a guide for the purpose set forth.

5. A side sill for railway house cars comprising a substantially vertical web, a substantially horizontal flange extending from the upper margin of said web, a substantially horizontal flange extending from the lower margin thereof laterally beyond said car to serve as a track for a sliding door, said sill being provided with means forming a guide for said door.

6. In a railway house car, in combination, a side wall provided with a door opening, a side sill construction including a substantially horizontal flange spaced below said door opening, and extending laterally beyond said side wall, whereby said flange is adapted to serve as a track for a door adapted to close said opening.

7. In combination, a car body, a side sill, a door opening in said car body, said sill being constructed and arranged to extend laterally beyond said car body to constitute a track for a door provided on said car body for closing said opening, said sill being provided with a flange forming guide and retaining means for said door.

8. In a side sill for a railway house car comprising, in combination, a structural member embodying a substantially vertical portion, a flange extending at right angles to said vertical portion, said vertical portion carrying a member having a downwardly extending spaced flange for the purpose set forth.

9. The combination with the posts and braces of a house car of a side sill, said sill having a flange positioned below said posts and braces, means rigidly securing said posts and braces to said side sill, said flange ex-

tending laterally beyond said posts and braces for the purpose set forth.

10. In side sill construction for a railway house car, an angular member having a substantially vertical portion, a substantially horizontal flange positioned below said portion extending laterally beyond said car, whereby said flange is adapted to serve as a track for a sliding door mounted upon said car, said flange having downwardly extending means adapted to form a guide and retainer for said door.

11. In a railway house car, in combination, a side wall provided with a door opening, a side sill construction including a Z shaped member positioned with one flange thereof extending substantially horizontally, said flange projecting beyond said side wall to serve as a track for a door adapted to close said opening, and a downwardly directed flange depending from said horizontal flange for the purpose set forth.

12. In a side sill construction for a railway house car comprising, in combination, a structural member embodying a substantially vertical portion, a substantially horizontal flange extending from the upper margin of said vertical portion, substantially horizontal oppositely extending flanges projecting from the lower margin of said vertical portion and a downwardly extending member carried by said sill adapted to serve as guide and retaining means.

13. The combination with the side wall of a railway house car provided with a door opening and a sliding door mounted on the outside of said wall to close said opening, of a side sill construction embodied in said car, a portion of said sill construction being positioned laterally beyond said wall and directly beneath said door, whereby said sill construction serves as a track for said door.

14. The combination with the side wall of a railway house car provided with a door opening and a sliding door mounted on the outside of said wall to close said opening, of a side sill construction embodied in said car, said sill construction including a flange projecting laterally beyond said wall to lie directly beneath said door for the purpose set forth.

15. The combination with the side wall of a railway house car provided with a door opening and a sliding door mounted on the outside of said wall to close said opening, of a side sill construction embodied in said car, said sill construction including a flange projecting laterally beyond said side wall to lie directly beneath said door, said flange having a downwardly extending portion for the purpose set forth.

16. The combination with the side wall of a railway house car provided with a door opening and a sliding door mounted on the outside of said wall to close said opening,

of a longitudinally extending substantially Z shaped member secured to said car adjacent one side thereof, the flanges of said member being positioned substantially horizontally, one of said flanges projecting laterally beyond said wall and directly beneath said door for the purpose set forth.

17. The combination with the side wall of a railway house car provided with a door opening and a sliding door mounted on the outside of said wall to close said opening, of a longitudinally extending Z shaped member secured to said car adjacent one side thereof, the side flanges of said member being positioned substantially horizontally, one of said flanges projecting laterally beyond said wall and directly beneath said door, said flange having a downwardly extending portion for the purpose set forth.

Signed at Chicago, Illinois, this 28th day of January, 1930.

WILFRED A. BEAUCHAMP.
